Primary Examiner — Dana L Meyrow(74) *Attorney, Agent, or Firm* — Oyen Wiggs Green & Mutala LLP(57) **CLAIM**

The ornamental design for a bottle, as shown and described.

DESCRIPTION

FIG. 1 is a top, front perspective view of a bottle showing my new design, the repeating circular details of the bottom surface not shown through the transparent material for ease of understanding;

FIG. 2 is a right side elevation view thereof, the left side elevation being a mirror image;

FIG. 3 is a top plan view thereof, the bottom surface details not shown through the transparent material for ease of understanding; and,

FIG. 4 is a bottom plan view thereof.

The design consists of the features of shape, ornament and configuration of the bottle as shown in the drawings.
